(57) **CLAIM**

The ornamental design for a grip for a die press, as shown and described.

DESCRIPTION

FIG. 1 is a front perspective view of a grip for a die press of the present invention;

FIG. 2 is a left side elevational view thereof;

FIG. 3 is a right side elevational view thereof;

FIG. 4 is a top plan view thereof; and,

FIG. 5 is a front elevational view thereof.

The broken line showing the die press is for illustrative purposes only and forms no part of the claimed design.
